UNITED STATES PATENT OFFICE.

CHARLES W. BOLTE, OF ATLANTIC CITY, NEW JERSEY.

EGG-CARRIER.

1,101,782.

Specification of Letters Patent. Patented June 30, 1914.

Application filed March 8, 1913. Serial No. 753,125.

To all whom it may concern:

Be it known that I, CHARLES W. BOLTE, a citizen of the United States, residing at Atlantic City, in the county of Atlantic and State of New Jersey, have invented a certain new and useful Egg-Carrier, of which the following is a specification.

This invention relates, generally, to cartons and particularly to cartons for the transportation of eggs, and it has for its object to provide a simple, comparatively inexpensive, and light weight receptacle in which the eggs may be packed for transportation without liability to damage or breakage, and it consists in the parts and combinations of parts hereinafter described and claimed.

In the accompanying drawings forming a part of this specification, Figure 1 is a side elevation, with the outer case partly broken away, of my improved egg carton. Fig. 2 is a perspective view of one of the trays. Fig. 3 is a vertical section through one of the trays. Fig. 4 is a plan view of one of the trays. Fig. 5 is a perspective view of the filler.

Similar numerals refer to similar parts throughout all the views.

Referring to the drawings the numeral 6 represents the box or case of my improved carrier and 7 the lid therefor. As shown the box or case is cylindrical in shape and having a closed bottom, and the lid is adapted to fit closely over its open end or top and is held against accidental dislodgment by a fastening device consisting of an elastic strip 8 having one end secured to a wire hook 9 and the other end to a wire loop 10, the extreme ends of said loop being formed with eyes and mounted on a wire 11 secured to the box or case. A similar wire loop 12 is pivotally attached to a wire 13 at the opposite side of said box or case, and both loops, 10 and 12, are bent as shown so as to extend over and onto the lid when the latter is in place and to be held in position when the hook 9 is caught over the loop 12, thus securing the lid in place and providing for the ready and easy examination of the contents of box or case.

The egg trays, as shown, consist of a ring or cylinder 14 forming a frame of a diameter adapted to fit snugly within the box or case, and having their bottom ends covered by a fabric 15, said fabric having its edge secured to said ring or cylinder. As

shown the fabric is roughly disk shaped in outline and notched, as at 16, along its edge and fastened by glue or paste or other adhesive substance to the outer surface of the ring or cylinder, but it may be secured to 60 said cylinder by stitching, as indicated in dotted lines Fig. 2, or by any other convenient means, the only essential being that the fabric be firmly secured to the cylinder or ring. The top of the ring or cylinder is 65 provided with a cover 17 of similar fabric similarly secured in place, and which is cross-slitted, as at 18, at four equi-distant points, so as to form openings to pockets or cells arranged on the underside of said fabric cover 17. The pockets or cells, 19, are made separate or independent of the cover and are stitched or otherwise secured thereto, as indicated at 20, Figs. 2 and 4, around the openings therein, so that an egg may be 70 readily pushed through the openings and into the pocket or cell. The pockets or cells are also secured by stitching to the bottom cover 15 in order to hold them in their relative position to the openings and to prevent 75 lateral movement of the eggs. Each of the trays is provided with a tape 21 which forms a handle, by which the same may be lifted or carried and inserted and removed from the box or case, said tape having its ends 80 secured to opposite sides of the trays by stitching or otherwise.

By reason of the construction and arrangement described the eggs are isolated one from the other in the tray so that it is 90 impossible for them to come into contact, thus minimizing the liability to breakage, and they are also held firmly and securely against other movement while in the pockets or cells.

The trays containing the eggs are arranged one on top of the other in the box or case, the bottom edge of the first tray placed in the box resting on the bottom of said box and each succeeding tray resting 95 on the top edge of the tray beneath it. In practice the box or case is made of a depth to hold a predetermined number of trays and to provide a space above the same to receive a filler 22, consisting of a short ring or cylinder having a fabric cover 23 at one end, which is secured thereto in a manner similar to that employed in securing the fabric to the trays. The filler 22 is placed, 100 fabric side or end down, on the top tray of 110

the series of trays in the box or case, thus forming a fabric protection for the eggs in the said tray and filling the case or box so that when the lid is in place the series of 5 trays will be locked in place.

While I have described the carton as cylindrical in shape it is obvious that it may be rectangular, or octagonal and equally good results obtained.

10 What I claim is:

1. A transportation tray for eggs, comprising a rigid frame having a fabric top and a fabric bottom, pockets or cells for receiving the eggs interposed between said 15 top and bottom and inclosed by said frame, said top being formed with openings corre-

sponding in position with said pockets or cells, and a case for receiving said tray.

2. An egg tray, comprising a frame having a fabric top and a fabric bottom, pockets or cells arranged between and secured to 20 said top and bottom, said top being slitted to form openings corresponding in position to the pockets and said slitted portions forming covers for said pockets. 25

In testimony whereof I affix my signature, in the presence of two witnesses.

CHARLES W. BOLTE.

Witnesses:

WM. J. BENNER,
CHARLES LOWELL HOWARD.
